UNITED STATES PATENT OFFICE.

ELMER F. RUDEEN, OF LOS ANGELES, CALIFORNIA.

CONDENSER.

948,432.

Specification of Letters Patent.

Patented Feb. 8, 1910.

Application filed July 6, 1909. Serial No. 505,983.

To all whom it may concern:

Be it known that I, ELMER F. RUDEEN, a citizen of the United States, residing at Los Angeles, in the county of Los Angeles and State of California, have invented new and useful Improvements in Condensers, of which the following is a specification.

This invention relates to a steam condenser and it involves a construction for the condensation of the steam by direct and intimate contact with the water and air in the condenser, the steam passing through the water in small sprays and the air being injected along with the steam. The air passes from the condenser after having passed through the water and carries off a large amount of the heat of the steam. The water is drawn off as the steam condenses, and new water supplied from time to time if necessary; but in the usual case it is not necessary to supply any or a large amount of water as the injected air carries off the heat of vaporization.

In the accompanying drawings, Figure 1 is a vertical central section of the improved condenser. Fig. 2 is a horizontal section taken on line 2—2 of Fig. 1.

Referring to the drawings 5 designates a tank or shell of suitable size and capacity for any particular condenser, being preferably constructed of sheet iron. At the bottom of the tank are two inlet pipes 6 and 7, for steam and air respectively. These pipes discharge into a compartment 8 which is walled off from the remainder of the tank by a head 9. This head is provided with apertures 10 which are controlled by upwardly opening valves 11, these valves being held normally closed by the pressure of water 12 in tank 5 above them. Head 9 is secured in the tank on an angle iron bracket 13 or other equivalent means, by bolts 14, so that it is removable for access to chamber 8.

Vertically spaced from each other in the tank above head 9 is a plurality of perforated plates 15, the number of these plates depending upon the size and design of the condenser. These plates are spaced apart and supported by rings 16, being laid loosely in the tank so that they are easily removable. They are perforated in the manner shown in Fig. 1, a small lip 17 being punched up out of the metal and leaving an opening below its edge as illustrated. These lips are punched so as to discharge the steam and

air passing therethrough in opposite directions on adjacent plates.

In the operation of this condenser steam and air are forced into chamber 8 in such proportions as experience may dictate best, water being placed in the upper part of the tank to about the level shown. When the steam and air pressure in chamber 8 becomes sufficiently great, valves 11 are opened and the mingled steam and air passes upwardly through water 12. The air having come into direct and intimate contact with the steam in chamber 8, has absorbed a large quantity of its heat. The steam and air being passed into the water and coming into more or less intimate contact therewith, gives up enough of its heat so that the steam is condensed. The air passes off at the top of the condenser, carrying with it a large amount of the heat of the steam. As the air will emerge from the condenser at practically the same temperature at which water 12 is kept, it is best to keep the water as near the boiling point as possible. In some cases the air will carry off a large enough quantity of heat to keep the temperature of the water below the boiling point, and, consequently, to condense all of the steam. In this case it is only necessary to draw off the water of condensation through outlet pipe 20. In other cases the air may not carry off a sufficient quantity of heat, and fresh cold water is passed into the condenser through inlet pipe 21.

The advantages of the present construction are these: the volume of the hot gases passed through the water is increased by the injection of air, thereby increasing the efficiency of the heat transfer from the gas to the liquid; and the injected air carries off a large amount of the heat of the steam.

Having described my invention, I claim:

1. A steam condenser, comprising a tank, a head in the tank dividing it into upper and lower compartments, means for introducing steam and air to the lower compartment, means for introducing and withdrawing water to and from the upper compartment, there being communication between the upper and lower compartments for the passage of the steam and air.

2. A steam condenser, comprising a tank, a perforate head dividing the tank into upper and lower compartments, upwardly opening valves controlling the passage of fluid through the perforation in the head, a series of vertically spaced perforate plates

- in the upper compartments, means to introduce and withdraw water to and from the upper compartment, and means to introduce steam and air to the lower compartment.
5. 3. A steam condenser, comprising a mixing chamber, means for introducing steam and air to the mixing chamber, a water chamber arranged above the mixing chamber, means for withdrawing the water from 10 the water chamber, and means for introducing mixed steam and air from the top of the mixing chamber to the bottom of the water chamber.
4. A steam condenser, comprising a tank, 15 a perforated head in the tank dividing it

into upper and lower compartments, means for introducing steam and air to the lower compartment, means for withdrawing water from the upper compartment, and upwardly opening valves preventing the downward 20 passage of water from the upper compartment through the perforations in the head.

In witness that I claim the foregoing I have hereunto subscribed my name this 26th day of June 1909.

ELMER F. RUDEEN.
